his Attorney.

UNITED STATES PATENT OFFICE.

FRANK A. SHIMANS, OF CHICAGO, ILLINOIS.

RAZOR.

1,210,220.

Specification of Letters Patent. Patented Dec. 26, 1916.

Application filed April 20, 1916. Serial No. 92,368.

To all whom it may concern:

Be it known that I, FRANK A. SHIMANS, a citizen of the United States, and a resident of the city of Chicago, county of Cook, and 5 State of Illinois, have invented certain new and useful Improvements in Razors, of which the following is a specification.

My invention relates to improvements in razors, and has for its object the production of a device of this character which will 10 be of improved construction, and efficient in use.

Other objects will appear hereinafter.

The invention consists in the combinations 15 and arrangements of parts hereinafter described and claimed.

The invention will be best understood by reference to the accompanying drawing forming a part of this specification, and in 20 which,

Figure 1 is a partially sectional front elevation of a razor embodying the invention, Fig. 2 is a partially sectional rear elevation of the device, Fig. 3 is a substantially 25 central section of the device, Fig. 4 is a top plan view thereof, and Fig. 5 is an enlarged section taken on line α — α of Fig. 1.

The preferred form of construction, as 30 illustrated in the drawing, comprises an elongated comparatively flat hollow body 1 adapted, in the employment of the razor, to constitute a handle. Rotatably mounted in the rear wall of the body 1, at the upper end thereof, is a stud 2, to which is fixed a 35 pinion 3. The front end of the stud 2 is squared for engagement with an opening of corresponding form which is provided centrally in a circular blade 4 which is adapted to be mounted upon said stud. 40 The connection between said stud and blade serves to lock the latter to said stud so that upon rotation of the stud, said blade will also be rotated. Said blade is held in operative position upon said stud by the upper 45 end portion 5 of the front wall of the body 1, said portion 5 being hingedly mounted, as at 6. Spring keepers 7 secured to the rear wall of the razor body are adapted to engage over the lateral edges of the wall member 5 to lock the same in operative position.

The construction is such, as will be seen, that upon release of the wall member 5 and forward rocking of the same, the blade 4

will be free for removal from the stud 2 for sharpening or replacement, as will be readily understood.

Carried by the wall member 5 is a guard 8 of arcuate form adapted to coöperate with the upper exteriorly projecting portion of the blade 4, as will be readily understood. 60 The guard 8 is secured in position by means of a screw 9 which passes through an elongated slot provided in said guard in order to permit of adjustment of the latter. In the operation of the razor, the blade 4 is rotated, such rotation being effected by means of a hand operable wheel 10 rotatably mounted in the body 1 with opposite sides projecting exteriorly through slots formed in the lateral walls of said body, said exteriorly projecting portions being adapted 70 for engagement by the thumb or fingers, as will be readily understood. The periphery of wheel 10 is knurled to facilitate rotation of the same. Said wheel is operatively connected with the blade 4 by means of a train of multiplying gears 11 interposed between the wheel 10 and the pinion 3, the arrangement being such, that when said wheel is rotated at a comparatively slow rate of 80 speed, the blade will be rotated at a much higher rate of speed.

In order to prevent the entrance of lather or other foreign matter into the body 1, during operation of the razor, strips 12 of rubber or other suitable material are provided at the upper end of said body secured to the front and rear walls thereof, which engage with the opposite sides of the cutting edge of the blade at the points of entrance into 90 the razor body. Said cleaning members 12, engaging with the opposite sides of the blade, serve to wipe off any foreign matter from the blade, and thus to prevent entrance of the same into the body of the razor, as 95 will be readily understood.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the 100 appended claims.

Having described my invention what I claim as new and desire to secure by Letters Patent is:

1. A razor comprising a hollow comparatively flat body; a stud rotatably mounted in said body on one wall of said body at one end thereof; a circular blade mounted on said stud, the opposite wall of said body being hingedly mounted; and means for normally holding said last mentioned wall in operative position, substantially as described.
2. A razor comprising a hollow comparatively flat body; a stud rotatably mounted in said body on one wall of said body at one end thereof; a circular blade mounted on said stud, the opposite wall of said body being hingedly mounted and adapted, when in operative position, to hold said blade in position on said stud; and means for normally holding said last mentioned wall in operative position, substantially as described.
3. A razor comprising a hollow comparatively flat body; a stud rotatably mounted

in said body on one wall of said body at one end thereof; a circular blade mounted on said stud, the opposite wall of said body being hingedly mounted; and keepers engaging with the lateral edges of said last mentioned wall for normally locking the same in operative position, substantially as described.

4. A razor comprising a hollow body adapted to constitute a handle; a circular blade rotatably mounted in said body and having a portion projecting from said body; cleaning devices in said body engaging with opposite sides of the cutting edge of said blade to prevent the entrance of foreign matter into said body; and means in said body for rotating said blade, substantially as described.

In testimony whereof I have signed my name to this specification in the presence of two subscribing witnesses.

FRANK A. SHIMANS.
